BATTERY ELIMINATOR

Application filed May 18, 1925. Serial No. 31,082.

This invention is a novel improvement in rectifying systems, and the principal object thereof is to provide a unit adapted to be used for supplying direct current of unvarying magnitude, and at multiple and variable voltages, from the ordinary alternating current electric light socket, to radio receivers, amplifiers, loud-speaking telephones, electromagnetic reproducers, telephone or telegraph systems, time clocks, relays, or any other electric receptive devices utilizing direct current.

Heretofore, radio receivers and the like, employing multiple electrode vacuum tubes for the detection and amplification of radio signals, have depended for their power upon dry-batteries, storage-cells, or so-called "battery eliminators." The inherent objections to the use of batteries and cells are numerous, and include the inconvenience, odors, and spilling of the electrolyte, as well as the constant wearing down of the batteries necessitating their re-charging or replacement. A number of radio devices have been marketed called "battery eliminators", their function being to rectify and filter the usual 110 volt alternating electric light current, obtained from the usual light sockets, and to apply it to the anodes of two or three electrode tubes. The main objection to the present types of "battery eliminators" is the production of a hum in the receivers or loud speakers of the radio sets, and hence these devices have usually been limited to replacing the "B" batteries only, their power rating being very low. Other objections to the usual "battery eliminators" prevent their widespread use in entirely replacing radio batteries.

Further objects of my invention are to provide a unit adapted to supply direct current at proper voltages and amperages to the anodes of multiple electrode vacuum tubes; to supply direct current at proper voltages and amperages to the filamentary cathodes of multiple electrode vacuum tubes; to perform the two preceding acts without impairing the quality of the radio reception or amplification by the presence of any hum caused by the alternating current generators; to perform the above acts with a

certain degree of independence from the character of the alternating current light socket supply (i. e. with regard to change in line voltage, phase, and frequency); and to possess a degree of adaptability that will permit its use on any type of radio receiver, speech or radio amplifier, telephone or electromagnetic reproducer, telephone or telegraph system, time clock system, relay, or the like. Another object is to provide one or more sources of rectified current in which potential disturbances arising either within or external to the supply transformer have no resulting effect in the source.

Still further objects of the invention are to provide a unit which may be used as a "B" battery supply, i. e., a unit to supply direct current up to 200 milliamperes at voltages ranging from 0 to 500 volts; or may be used as an "A" battery supply, delivering direct current up to 10 amperes, at voltages from 0 to 50 volts; or may be used as a combination "A" and "B" unit.

I will explain the invention with reference to the accompanying drawings, which illustrate practical embodiments thereof to enable others skilled in the art to adopt and use the same, and will summarize in the claims the essentials of the invention, the novel features of construction, and the novel combinations of parts, for which protection is desired.

In the drawings:

Figure 1 is a diagrammatic view of my rectifying unit including a filter arrangement;

Figure 2 illustrates the manner of winding the transformer and bringing out the leads;

Figure 3 is a bridge showing the relation between the various capacities to produce a balance while Figure 4 is a plot of the conventional B-H magnetization curve.

Referring to Figure 1, it will be noted that the unit comprises two separate and distinct systems the upper being designed to furnish energy of high voltage and low amperage for use in the plate circuit of a thermionic amplifying arrangement while the lower system is adapted to energize the filamentary circuit of the amplifier giving a relatively

low potential but high amperage within the limits set by the tube rectifiers.

P_1 and P_2 represent two primaries arranged in series and having applied across the inner terminals the usual 110 volt alternating current supply. The secondary consists of two groups of inductors each containing four coils, making eight in all for a complete "A" and "B" potential supply.

10 As will be apparent, the number of turns in each coil depends upon the individual load, in members 1 and 2 the turn ratio should provide a slight step-up in potential if the power supply is of the ordinary house voltage since the load is plate energization of the radio set. However, all the remaining coils furnish a step-down voltage translation in supplying a load which necessitates a relatively low potential i. e. either the filament of each 15 rectifier or that of the radio set. It will be noted that coils 2 and 6 are wound in a direction opposite to coils 1 and 5 respectively for the reason to preserve proper polarity of the rectifier anodes giving the effect of two 20 valves in parallel over a portion of cycle for each load centering in the amplifier.

The outer terminals of coils 1 and 2 are joined by an equipotential conductor from whence connection is taken by lead D to one 30 side of the amplifier load; the inner terminals provide potential for the opposite sets of plates in rectifier 10, current passing through conductors C and E. The extreme terminals of coils 3 and 4 are joined together 35 to form the other side of the amplifier load circuit, while the inner terminals are in electrical connection with the cathode of rectifier 10 through resistors 12 and 13. For regulating the degree of filament incandescence 40 I utilize duplex rheostat 14 operating to alter simultaneously the resistances in each leg of the cathode circuit; this resistance is effective in maintaining constancy of potential across the outgoing lines if the alternator voltage 45 changes. The lower group of coils consisting of members 5, 6, 7 and 8 have the same secondary connections with respect to rectifier 11 and its specific load as was explained in regard to the upper group. From the foregoing 50 it will be understood that the secondary leads resolve themselves into as many groups of threes as there are immediate loads, the groups being taken directly from the mid-position of each pair of coils. Referring 55 now to Fig. 2, I show diagrammatically, the manner of winding the coils to effect capacity balance between the different windings and effective ground. While the turn ratio of the transformer in Figure 1 is other than unity, 60 I propose to show for clearness a 1:1 relation in Figure 2. On core 15, which may be of the shell type I wind the primary in two sections between flanges 16 of a spool made of insulating material, as vulcanite, ebonite and the like, having central partition 17 of a con-

ducting material for reasons to be stated hereinafter. About the periphery of coils P_1 and P_2 , there is affixed an electrostatic shield 18 of a metal, as copper and the like. This electrostatic shield, as is customary, consists of a piece of copper which almost, but not quite, surrounds the coil. Hence, while this strip acts as an electrostatic shield, the lack of a complete peripheral circuit prevents it from being a short circuited secondary. One 70 of the secondary groups consisting of a pair of coils S_1 and S_2 is then wound about the shield, after which a second metallic shield is wrapped about the first group of secondaries to form a support for the next layer of 75 windings. This group S_1 and S_2 may be either coils 1 and 2, or 3 and 4, or 5 and 6, or 7 and 8. Then another group of coils S_1 and S_2 is wound over the first group after the shielding has been put into place. In case 80 only one rectifier with four secondaries were to be used, as for example, the top part of Figure 1, P_2 would be divided into two parts on the same idea as P_1 and P_2 are divided up and then S_1 and S_2 of each group would 85 be wound on. The shielding 18 is, of course, grounded to 17 and the outer casing. The transformer in its final form comprises a number of coil pairs concentrically mounted, each coil of a pair being separated by the partition while the pairs are electrostatically shielded from one another by the metallic 90 layers. The number of pairs of coils correspond to the several loads which in the case of filament and plate energization as shown 95 in Figure 1 would necessitate four. It will be seen that if the coils have been wound symmetrically on the spool, the leads terminating the primary and each pair of secondaries 100 will be equidistantly disposed with respect to separator 17 and the end portions of the core. In view of the fact that distributed capacity of the windings may be considered as operating at the ends of the coils in the form of lump capacity, the effect of capacity 105 to ground as represented by the core and middle separator may be diagrammatically indicated by elements C_1 , C_2 , C_3 , C_4 , C_5 , C_6 , C_7 and C_8 . Thus it will be seen that in its broader 110 aspects, my invention has for one of its results—the winding of a transformer in such a way that each coil is so related electrostatically to the remaining coils that outside disturbances effecting one, tend to effect all and are balanced out. This requires the primary 115 to be in at least two parts and composing half of the bridge and two secondaries composing the other half of the bridge. In this way, line disturbances are symmetrically distributed in such a way that they are cancelled within the 120 transformer. Of course, S_1 and S_2 in the bridge in Figure 3 may be considered to either represent all S_1 coils and all S_2 coils collectively, or those coils individually. In that 125 case, there will be just as many bridges as 130

there are S_1 coils, but all those bridges will be so related to each other that disturbances from the line will be cancelled in all of them. In this way, the necessity for buffer condensers across the secondary is reduced, if not, eliminated.

In Figure 3, I have reconstructed the arrangement of windings and their capacity equivalent in the form of a bridge. It is apparent that if the several impedances balance each other in accordance with the properties of the bridge, extraneous disturbances whether of an audio or radio frequency nature causing undulations of potential in the primary or any of the secondaries, produce no deleterious effect across the terminals of the amplifier plate energization and filament loads because with respect to these variations points X and Y, representing the relation in the bridge between the equipotential conductors of the primary and each of the secondaries, are at the same potential. Stated in another way, the effect of distributed capacity which ordinarily offers a ready path for high frequency variations in potential has been nullified by the specific position of transformer leads with respect to the metallic casting, thus introducing a capacity balance. The latter also functions effectively to necessitate a proper division of load between both rectifiers. Furthermore, it is apparent that the bridge may consist in capacity to a ground other than that shown for example, between the terminus of the primary and secondary windings and any symmetrically placed surface of zero potential such as the electrostatic shield separating layers. In this case, the ground from whence to derive the necessary balance of impedance is transferred from the core and separator to the concentric cylinders. Duplex rheostat 14 provides equal changes of resistance in the rectifier filament leads, preserving equality of impedance to maintain the bridge. In view of the network, electrical balance will exist under all conditions of voltage transformation and is applicable to each and every coil pair symmetrically wound on the same core. For rectifiers 10 and 11, the heated cathode type containing two electrodeal elements is preferred although I illustrate a conventional three electrode device in which the grid and plate members are connected together to form an anode of comparatively large area; this form of tube is available in the market. All types of rectifiers including gaseous conduction between solid electrodes and electrolytic devices, yielding an order of voltage and current demanded by the load are adapted to my system. However it is obvious that the number of pairs of coils should be modified to accommodate the particular form of unilateral conductor utilized. From each rectifying unit, the current passes through filter F to the ultimate load which in the upper system,

comprises plate energization of an amplifying arrangement. If desired, a potential of lower order for a detector may be obtained by including structure indicated by adjustable resistance 19 to produce the necessary potential drop. The voltage applied across the plates of the amplifier may be regulated by rheostat 14 or in any manner known to the art. All forms of low pass filters may be employed; the type illustrated comprises series choke and shunt condensers. In the lower system, rheostat 20 for regulating the current passing the amplifier cathode load is connected preferably in series with the outgoing line.

As an expedient for preventing changes in voltage due to poor regulation of the alternator, I propose to operate the core of the transformer either at the lower or the upper bend of the magnetization curve applicable to the particular core material. Referring now to Figure 4 it will be apparent that if either of the points A and A' are selected by controlling the terminal voltage of the alternator or by properly dimensioning the cross-section of core to produce a particular root mean square value of flux density, proportional changes in magneto-motive force do not yield corresponding variations in flux due to the decrease in slope of curve at the chosen positions. However, it is preferable to operate at the upper bend for economic reasons.

If desired, the transformer or any part thereof may be placed within a case of conducting material as steel, to prevent leakage flux from adversely affecting the remaining apparatus.

In view of the foregoing it will be apparent that the upper and lower rectifying systems may each be fed from individual transformers and utilized in the manner shown as a combined source of filament and plate energization for a radio system or singly for either of the energization purposes.

I do not limit my invention to the exact forms shown in the drawings, for obviously changes may be made therein within the scope of the claims.

I claim:

1. In a rectifying system comprising an input circuit subject to extraneous disturbances, an output circuit, a transformer disposed between circuits and including a capacity coupling between windings whereby the disturbances affect said output, the method of nullifying said coupling which consists in introducing additional capacity effects in the transformer to form with the coupling capacity a balanced network.

2. In combination, a transformer with a rectifier load, said transformer comprising a plurality of pairs of windings, each pair representing sections of equal impedance and having outer terminals electrically joined to

gether, the leads from the inner terminals being brought out from the mid-point of each pair to form with said impedance a balanced electrical bridge.

5 3. In combination, the following: a source of alternating current, a direct current load that demands high constancy of potential, a rectifier and transformer disposed therebetween having primary and secondary windings sectionized to form inner and outer terminals, equipotential conductors joining the last-mentioned terminals, the primary and secondary inner terminals passing to said source and rectifier respectively.

15 4. In combination, a source of alternating current subject to potential disturbances, a direct current load that demands high constancy of potential, a rectifier and transformer disposed therebetween having primary and secondary windings with distributed capacity and a metallic shield between windings to form with the distributed capacity a bridge whereby the disturbances are precluded from affecting the load.

25 5. In combination, a source of alternating current, a direct current load, a transformer and a double unit rectifier disposed between said source and load and means operating in conjunction with the capacity inherent 30 in the transformer windings, for maintaining the proper division of load between the units of said rectifier.

6. In a rectifying system comprising an input circuit subject to extraneous disturbances, an output circuit, a transformer including capacity coupling between windings whereby the disturbances affect the output circuit, the method which consists in introducing and proportioning capacity effects 40 in the transformer with respect to ground to form with the coupling capacity a balanced network.

7. In a rectifying system comprising an input circuit subject to voltage disturbances, 45 an output circuit, a transformer including capacity coupling between windings whereby the disturbances affect the output circuit, the method which consists in utilizing the capacity effects in the transformer with respect to ground to form with the coupling capacity a balanced network and in operating the transformer core at a relatively high flux density whereby the disturbances are 50 prevented from passing to the output circuit.

55 In testimony that I claim the foregoing as my own, I affix my signature.

ROLAND F. BEERS.
